SNOW MELTER

Application filed April 18, 1927. Serial No. 184,754.

- This invention relates to improvements in portable apparatus for melting snow and particularly to devices of this character adapted for use with a mechanical loader.
- 5 In cities and other centers of congested population the removal of snow from streets presents a serious problem. The present practice is to plow the snow to the sides of the streets, pick it up with some sort of a mechanical loader, drop it into trucks and haul it to some place where it can be dumped. The cost of removing snow in this way is excessively high due principally to the cost of hauling.
- 10 15 20 25 30 35 40 45 50 55 60 65 70 75 80 85 90 95 100
- We are aware, of course, that it has heretofore been proposed to dispose of snow by passing it through some form of melting apparatus and that many devices for disposing of snow in this way have been proposed. These devices include means for utilizing the heat generated by the combustion of different fuels, and in some cases, it has been proposed to project flames from torches and the like directly upon or against the snow.
- It is well known that kerosene or fuel oil when properly burned with sufficient oxygen to produce a rapid combustion generates intense heat. It is also well known that snow is a poor conductor of heat. For this reason, where a jet of fire is projected directly onto the snow it simply melts a hole immediately about the flame and has no appreciable effect upon the snow which is not directly in its path. This is also true where steam or hot gases emerge through openings directly into the snow.
- In order to attain a high degree of efficiency in a device of this character it is necessary not only to bring the snow into contact with highly heated surfaces or gases but to provide some means whereby the snow may be heated either successively or simultaneously on all sides. Most of the snow melters are designed to heat directly from the bottom or at least to subject the snow to heat applied in fixed directions relative to its movement through the melting apparatus. We propose not only to attack the snow by hot gases and by contact with hot surfaces but to provide an apparatus of such design that the snow
- as it melts will fall through the apparatus by gravity so that the separate chunks thereof will be turned about in falling and successively subjected to heat in all directions.
- The primary object of our invention therefore is to provide a snow melting apparatus which will economically utilize the intense heat generated by the combustion of kerosene or fuel oil with the oxygen of air and with this end in view to provide a device in which the snow will be tumbled about during the melting process and thus be successively subjected to heat in all directions. Another object of our invention is to provide a device of this character in which the burners or torches will be located in conveniently accessible positions wholly exterior of the device where the character of the combustion may be observed at all times and where, in case of extinguishment, the burner may be readily relighted or will be automatically relighted by another burner. Another object of our invention is to provide a device of this character in which the direction of the projected flames may be varied somewhat to secure the most economical operation on wet or dry snow or ice. Another object of our invention is to provide a device of this character equipped with a pumping means for forcing the water produced by the melting of the snow or ice to a higher elevation where it becomes necessary or desirable to dispose of the water in this way. Still another object of our invention is to provide a device of this character which is adapted to be readily moved from place to place and particularly adapted to be drawn behind and used in connection with a mechanical snow loader.
- With these objects in view our invention includes the novel elements and combinations and arrangements of elements described below and illustrated in the accompanying drawings, in a more or less typical way, in which—
- Fig. 1 is a plan view of the receptacle into which the snow is dumped;
- Fig. 2 is an elevation view, in half section, of the snow receptacle showing one of the torches used in connection therewith;
- Fig. 3 is a plan view of our device;

Fig. 4 is a side elevation view of our device; and

Figs. 5, 6 and 7 are detail views illustrating an adjustable torch support.

5 In its preferred form, our snow melter comprises a hollow receptacle, 1, open at the top and substantially closed at the bottom except for a central opening, 2. The walls of the receptacle, 1, are formed of outer and inner 10 plates of iron or steel, 3 and 4, respectively, slightly spaced from each other and between which is interposed a layer, 5, of a heat insulating material such as asbestos. Inside of this receptacle are provided a plurality of inverted, frusto-conical baffles, 6, 7 and 8, respectively, having comparatively large central openings, 9, 10 and 11, respectively. In the drawings we have shown three of these baffles.

20 Supported upon the baffle, 7, by the legs, 12, is an upright, hollow, conical baffle, 13, formed of metal. The base of the cone, 12, is somewhat above the baffle, 7, so that an annular space is provided between baffles, 7 and 13. 25 The vertex of the conical baffle, 13, is somewhat above the opening, 9, in baffle, 6, and baffle, 13, is so adjusted in relation to baffle, 6, that snow sliding down the inclined surface of baffle, 6, will not pass directly into or 30 through the annular opening between baffles, 7 and 13, but will slide against the surface of baffle, 13, and drop on baffle, 7. Baffle, 13, is preferably imperforate except for a few comparatively small holes, 14, near the top. The 35 purpose of keeping this baffle imperforate is to retain the hot gases against the inner side thereof and thus maintain the baffle extremely hot, although it is advisable to provide vents near the top for a slight circulation.

40 Supported upon the baffle, 8, by the legs, 15, is the perforated frusto-conical baffle, 16, which is open at the top as shown at 17. The bottom of the baffle, 16, is somewhat raised above the surface of the baffle, 8, to provide an 45 annular space there between, and the truncated portion at the top is somewhat above the opening, 10, in baffle, 7. In other words this conical baffle is so placed in relation to baffle, 7, that snow falling upon baffle, 7, and sliding 50 downwardly will be projected directly against the heated surface of baffle, 16, and will slide downwardly or drop on baffle, 8.

The receptacle, 1, is provided with suitably disposed openings through which jets of flame are projected from torches, 18, disposed about the receptacle. These torches are arranged in three vertically disposed sets or tiers. Those of the upper set project flames through six openings, 19, which are 55 arranged somewhat above the level of opening, 9, in baffle, 6, but below the baffle. The second set of torches project jets of flame through the four openings, 20, and against the outer side of baffle, 7. The lower set project 60 flames through the four openings, 21, and

against the outside of baffle, 8. All of these openings are preferably in staggered relation as shown.

Referring particularly to Figs. 3 and 4, it is contemplated that our device with all of its equipment will be mounted upon a truck body, 22. The snow receiving receptacle will be vertically mounted as shown in Fig. 4 and supported by any suitable means such as the supports, 23, and the truck, will be provided with a sump, 24, beneath the center of the snow receptacle and into which the water from the melted snow will flow. Under ordinary conditions this water will be permitted to flow through the sump from the valve, 25, so directly onto the street and thence flow along the street to the sewer. Where the snow is being removed from a hill it is sometimes necessary to pump the water from the sump and convey it through a hose for some distance along the street. Where such is the case, there may be provided a pump, 26, operated by a gasoline engine, 27, having a radiator, 28, and which will withdraw the water from the sump through the pipe, 29. 90 The pump is provided with a threaded discharge opening, 30, onto which a hose may be coupled.

Referring to Figs. 3 and 4 we have illustrated a convenient means for supporting the burners. Each burner is provided with a regulating valve, 31, connected to the pipe system which in turn is connected with the fuel tank, 32. All the pipes which support the burners are connected together, as shown at 33 and 34, and supported by vertical pipes, such as 35 and 36. The burners themselves might be supported upon the same pipes but I have illustrated a separate supporting system comprising the connected circular pipes, 37, 38 and 39, supported upon the vertical pipes, 40. Each burner, 18, is mounted on trunnion bearings, 41, which are riveted or otherwise secured to the supporting pipes. The burners, 18, are tiltable in the trunnions, as shown in Fig. 6, and they may be locked in any position by means of the wing nuts, 42. The valves are connected with the burners by flexible pipes, 43.

It is necessary to feed the fuel to the burners under pressure, and for this reason we have provided a compressor, 44, adapted to be driven by the engine, 27, to compress the air in the fuel tank, 32, through the pipe, 45.

The operation of our device is as follows: 120 Snow which is dumped into the top of the melter from a mechanical loader falls upon hot baffle 6, and hot baffle, 13, and is also subjected to attack by hot gases rising between the baffles. It begins to melt immediately, from the bottom, and slides down both baffles, 6 and 13, where it is struck directly by flames projected through openings, 19. In passing 125 through the annular opening between baffles, 6 and 13, chunks of the partially melted snow 130

are broken off and fall upon baffle, 7, where they are subjected to heat on all sides. Here, the snow is further melted and slides down against hot baffle, 16, and from there down 5 to baffle, 8, and thence, in the form of water, to the sump, 24. In addition to melting by contact with the hot baffles, hot gases and flames are projected from the torches directly against the snow on one side, and the 10 hot gases from the torches below attack the snow on the opposite side. We thus utilize, for melting, both heated surfaces and the direct contact of the hot gases as projected and as they tend to rise through the apparatus. 15 It is well known that snow falls vary in character from heavy to light, and that sometimes a quantity of ice is encountered with the snow. For this reason we have mounted each of the burners on adjustable 20 trunnions so that the direction of the projected jets of flame may be varied to impinge directly upon the outsides of the baffles, or be projected substantially parallel to the outside of the baffles. The jets of 25 flame at the points where the combustion first begins, and for a considerable distance therefrom are protected from snow and water and therefore will not be extinguished. Furthermore, each jet is independent of all 30 the others and may be separately regulated to produce the most efficient results. It is practically impossible to extinguish a jet without shutting off the fuel supply because the jet of fuel will be ignited by an adjacent 35 burner.

While we have described our invention in its preferred form it is to be understood that the words which we have used are words of description rather than words of limitation, 40 and that changes within the purview of the appended claims may be made without departing from the true scope and spirit of our invention in its broadest aspects.

What we claim is—

- 45 1. A snow melting device comprising a receptacle provided, intermediate the top and bottom thereof, with a plurality of baffles comprising conical surfaces arranged alternately in upright and inverted relation to provide a comparatively tortuous passage for snow falling therethrough, and means for projecting jets of flame against and between said baffles.
- 55 2. In a snow melting device, the combination with a receptacle open at the top and provided, intermediate the top and bottom, with a plurality of vertically spaced, oppositely inclined baffles, of means for projecting jets of flame against and between said baffles.
- 60 3. In a snow melting device, the combination with a receptacle open at the top and provided, intermediate the top and bottom with a plurality of spaced baffles downwardly and inwardly inclined from the sides thereof 65 and open at the center, of a plurality of baffles

oppositely inclined to said first mentioned baffles and projecting through the central openings therein, and means for projecting converging jets of flame between said first mentioned baffles.

4. In a snow melting device, the combination with a receptacle adapted to hold the snow during the melting process and provided with openings in the sides thereof, of a plurality of liquid fuel burners disposed around said receptacle opposite said openings and adapted to project jets of flame through said openings from points exterior of said receptacle.

5. In a snow melting device, the combination with a receptacle adapted to hold snow during the melting process and provided with a plurality of downwardly inclined, spaced baffles therein, and openings in the sides thereof between said baffles, of a plurality of liquid fuel burners mounted exterior of said receptacle opposite said openings and adapted to project jets of flame into said receptacle through said openings, and means for varying the direction of throw of said jets to project the flames either against or between said baffles.

6. In a snow melting device, the combination with a receptacle open at the top and provided with a plurality of vertically spaced, inclined baffles therein, of a plurality of liquid fuel burners arranged in vertically spaced sets about the exterior of said receptacle and adapted to project jets of flame through openings in the sides thereof between said baffles.

7. In a snow melting device, the combination with a receptacle open at the top and provided with a plurality of spaced baffles downwardly and inwardly inclined from the sides thereof and open at the center, of a plurality of baffles oppositely inclined to said first mentioned baffles and disposed within the central openings thereof, and a plurality of liquid fuel burners disposed about the exterior of said receptacle and adapted to project converging jets of flame through openings in the sides of said receptacle beneath said first mentioned baffles.

8. A snow melting device comprising the combination with a receptacle open at the top and provided with a plurality of inverted frusto-conical baffles extending inwardly from the sides thereof and having openings at the center, of a plurality of baffles comprising upright conical surfaces disposed within said central openings and slightly spaced from said first mentioned baffles to provide a comparatively tortuous passage for snow falling through said receptacle, and a plurality of liquid fuel burners disposed about the exterior thereof adapted to project jets of flame through openings in the sides of said receptacle and against said baffles.

9. In a snow melting device, the combina-

tion with a receptacle open at the top to receive the snow, of means for projecting converging jets of flame into said receptacle at various stages between the top and bottom thereof, and means in said receptacle forming a tortuous, downwardly extending passage somewhat remote from the sides of said receptacle to permit the fall therethrough of snow in comparatively large bodies but adapted to turn the falling snow to expose different portions thereof to said jets of flame.
